UNITED STATES PATENT OFFICE.

FRANK B. BRADLEY, OF CHICAGO, ILLINOIS.

ADJUSTABLE SWITCH-ROD.

SPECIFICATION forming part of Letters Patent No. 650,892, dated June 5, 1900.

Application filed March 1, 1900. Serial No. 6,907. (No model.)

To all whom it may concern:

Be it known that I, FRANK B. BRADLEY, a citizen of the United States, residing at No. 3819 Prairie avenue, Chicago, in the county 5 of Cook and State of Illinois, have invented certain new and useful Improvements in Adjustable Switch-Rods, of which the following is a specification.

My invention relates to certain new and 10 useful improvements in railway-switches; and its primary object is to provide a simple, strong, and easily-operated adjusting device for connecting the switch-rails and the switch-rod, so that the switch-rails may always be 15 maintained and held securely in their proper position and easily adjusted as occasion requires.

Another important object of this invention is to provide connecting devices between a 20 switch-rod and a switch-rail which can be adjusted as required to a very fine degree, so that the position of the switch-rails may be regulated and maintained with the greatest possible accuracy and security; and a fur- 25 ther object of the invention is to provide a connection between a switch-rod and a switch-rail of great strength and whose adjustable features are of such a character that they will not be injuriously affected by exposure to the 30 elements, but always remain in a condition which will permit of the proper adjustment of the rails.

With these and other ends in view the invention consists in the peculiar construction 35 and arrangement of parts hereinafter described, and comprising, essentially, a rectangular block or plate having a corresponding seat in a chair connected with the switch-rail and provided with interlocking features 40 to secure it in its seat with the chair and a bolt passing through said block and connecting the same with the switch-rod, all of which will be fully described and claimed herein- after.

45 In the accompanying drawings, Figure 1 illustrates my invention, showing a longitudinal sectional view of a switch-rod, locking-block, and chair connected with a switch-rail. Fig. 2 is a plan view of the chair, the 50 top of the block being partly broken away to show the interlocking features. Fig. 3 is a cross-sectional view on the line 3 3 of Fig.

1. Fig. 4 is a sectional view showing a block provided with a concentric bolt-opening. Fig. 5 is a plan view of the chair, showing the locking-block in place and having its top partly broken away to show the interlocking features. Fig. 6 is a perspective view of the locking-block illustrated in Figs. 4 and 5 and inverted. Fig. 7 is a plan view of the chair, 60 showing the locking-block and its flange, both provided with interlocking features corresponding to those surrounding the recess in the chair and along its flanges, this view being partly in section. Figs. 8 and 9 illustrate 65 a rectangular locking-block provided with interlocking features on all four of its sides and having an eccentrically-located bolt-opening.

Referring to the drawings, in which like letters of reference denote corresponding parts 70 in all of the figures, A designates the track-rail, B the switch-rail, and C the switch-rod, with which my invention is embodied. This switch generally extends under both track-rails and between two of the ties, and it is 75 preferably provided with my improved adjusting and locking devices near each end for each switch-rail, although this is not necessary. An ear or plate F is rigidly secured to the switch-rod, and it extends longitudinally 80 thereof to form a jaw M between itself and the rod, this jaw being arranged to receive the chair G, which is suitably fastened to the switch-rail. The chair is provided with the upwardly-extending side flanges g and end 85 flange g', which serve as a guide for the flange L of the locking-block K, which block is ar- ranged in a socket-opening H in the chair and provided with suitable interlocking fea- 90 tures. The block is rectangular in form, and it may be square, as shown in Fig. 2, or ob- long, as shown in Fig. 5, and, furthermore, it may be concentrically connected with the switch-rod, as shown in Figs. 5 and 7, or ec- centrically connected therewith, as shown in 95 Figs. 2, 8, and 9, the bolt K passing through the switch-rod, the jaw F, and opening J in the locking-block, and connecting the parts rigidly together.

In order to secure an adjustment for the 100 locking-block in the socket of the chair and maintain the block rigidly in its adjusted re- lation to the chair, I provide two or all of the side edges of the block and the side walls of

the socket-opening H with interlocking features, consisting, essentially, of interlocking teeth formed by serrating or corrugating the engaging parts. These teeth P and the intermediate depressions on the side walls of the socket correspond with the teeth Q on the sides of the locking-block, so that the locking-block may be moved along in the socket to any position and dropped into place and fit easily, but yet snugly, in position. In order to increase the strength of this locking connection, I may provide the edges of the flange L with serrations Q' to engage the serrations P' on the flanges g of the chair, Fig. 7, the teeth of these serrations constructed to interlock with each other in the manner previously described, and thus adding considerable to the strength of the device, rendering it able to withstand the longitudinal strain to which the block and chair are subjected. If the block is square in shape, all four sides may be provided with the serrations; but if the block is oblong the two long sides thereof are serrated, as shown in Fig. 5, and it will only be necessary to provide the long side walls of the socket with serrations, as the drawings show.

It will be observed from the foregoing description that the switch-rail can be adjusted with relation to the switch-rod by arranging the locking-block in its proper position in the socket, and the interlocking features between the locking-block and the chair permit a certain range of adjustment, so that the position of the rail may always be accurately and positively fixed; but to secure a sufficiently-wide range of adjustment with a block concentrically connected with the switch-rod it would be necessary to provide interlocking features between the block and the chair of such a degree of fineness as would considerably increase the cost of manufacture and also result in rapid deterioration on account of the fact that the device is exposed to the action of the elements and under considerable strain and jar whenever a train passes. For this reason and in order to secure an adjustment of the widest range I prefer to provide an eccentric connection between the block and the switch-rod, which is accomplished by locking the bolt-opening J eccentrically in the block, Figs. 8 and 9. The result of this eccentric connection between the block and the switch-rod is that adjustments of almost an unlimited number are possible, it being simply necessary to adjust the switch-block forward or backward in the socket to its approximate position and then rotate the same until those edges of the block are in engagement with the side walls of the socket, which will give the finest adjustment and secure the switch-rail and switch-rod in their correct positions.

By referring to Figs. 8 and 9 it will be noticed that if the locking-block is advanced bodily the distance of one tooth it will actually move the chair a distance equal to that

between the centers of two teeth, and this distance may be too great for the proper adjustment of the switch-rail. Thereupon the locking-block is rotated in a direction and to a position which will reduce the actual movement of the chair to a fractional part of the distance between the centers of two teeth, and the locking-block, having four sides, can be moved so that the switch-rod and switch-rail will be held securely in their exact proper relation to each other, as the adjustment of the locking-block with relation to the chair is reducible to very fine degrees. It will of course be understood that by the same means the movement of the chair and the switch-rail can be correspondingly increased beyond the distance between the centers of two teeth. My invention therefore provides an adjustable connection between a switch-rod and a switch-rail which is very simple in character, strong, and easily manipulated to secure the proper adjustment between the rod and rail. It is also an important feature that the adjustment can be effected in such a fine degree and by simply turning the locking-block in its proper position. When the locking-block is constructed eccentrically, as just described, the adjustments to be obtained by rotating the block are so minute that it will not be necessary to construct the interlocking features with such a degree of fineness as would be necessary to obtain the same adjustments with a concentrically-arranged locking-block, Fig. 7. As a matter of fact these interlocking features (shown in Figs. 8 and 9) may be made with comparative coarseness, and to such extent the cost of manufacture is lessened and the life of the device is increased, as the action of the elements on the comparatively-coarse interlocking features would not be so injurious as upon interlocking features of a fine finish. I may use one of these connections on the switch-rod or I may have one for each of the switch-rails, and to readjust the parts it is only necessary to remove the bolt K and slip the switch-rod off of the chair, so that the locking-block can be rearranged in the socket of the chair, after which the switch-rod is again bolted in place.

Having thus fully described my invention, what I claim, and desire to secure by Letters Patent, is—

1. The combination with a switch-rail and a switch-rod, of a chair rigidly secured to the switch-rail at one end and provided with a socket-opening, a rectangular block arranged in said opening and provided with interlocking features to secure it to the chair, and a bolt securing said block to the switch-rod, substantially as described.

2. The combination with a switch-rail and a switch-rod, of a chair rigidly secured to the switch-rail at one end and having its other end provided with an oblong socket-opening, a rectangular locking-block arranged in said socket-opening and provided with interlocking features to secure it to the chair, and a

bolt passing through the switch-rod and the block to connect the same together, substantially as described.

3. The combination with a switch-rail and a switch-rod, of a chair rigidly secured to the switch-rail at one end and having its other end provided with an oblong socket-opening, a square locking-block arranged in said opening and provided on its sides with interlocking features to secure it to the chair, and means for connecting said block to the switch-rod, substantially as described.

4. The combination with a switch-rail and a switch-rod, of a chair rigidly secured to the switch-rail at one end and having its other end provided with an oblong socket-opening, a locking-block arranged in said socket-opening, and having interlocking features to secure the block to the chair, said features consisting of teeth on the sides of the block engaging corresponding teeth on the side walls of the socket-opening, and means for securing the block to the switch-rod, substantially as described.

5. The combination with a switch-rail and a switch-rod, of a chair rigidly secured to the switch-rail at one end and having its other end provided with a socket-opening, side flanges on said chair, a locking-block arranged in the socket-opening and provided with a flange extending over the opening, and interlocking features between the block and the side walls of the opening and between the block-flange and the chair-flanges, substantially as described.

6. The combination with a switch-rail and a switch-rod, of a chair rigidly secured to the switch-rail at one end and having its other end provided with a socket-opening, a locking-block arranged in said opening and capable of a bodily longitudinal adjustment therein, and a bolt securing said locking-block to the switch-rod, substantially as described.

7. The combination with a switch-rail and a switch-rod, of a chair rigidly secured to the

switch-rail at one end and having its other end provided with a socket-opening, a locking-block in said opening and capable of a bodily longitudinal adjustment therein, and a bolt eccentrically connected with the locking-block and securing the same to the switch-rod, substantially as described.

8. The combination with a switch-rail and a switch-rod, of a chair rigidly secured to the switch-rail at one end and having its other end provided with an oblong socket-opening, a square locking-block arranged in said opening and capable of a longitudinal adjustment therein, interlocking features between the block and the chair and a bolt eccentrically connected with the block and securing the block to the switch-rod, substantially as described.

9. The combination with a switch-rail and a switch-rod, of a chair rigidly secured at one end to the switch-rail and having its other end provided with a socket-opening, a locking-block arranged in said socket-opening and having an eccentrically-located bolt-opening, interlocking features between the locking-block and the chair, and a bolt securing the block to the switch-rod, substantially as described.

10. The combination with a switch-rail and a switch-rod, of a chair rigidly secured to the switch-rail at one end and having its other end provided with a socket-opening, a series of teeth along two walls of said opening, a locking-block arranged in the opening and having all of its sides provided with teeth adapted to interlock with those of the chair, said socket-opening being elongated to permit of a longitudinal adjustment of the block therein, and a bolt eccentrically connected with the block and securing the block to the switch-rod, substantially as described.
